T5 Side Mount LED 3000K 120 DEG replacement lamp; and S8 Side Mount LED 3000K 120 DEG replacment lamp, both from Klchler.com, visited May 30, 2017. (2 pages).*

Primary Examiner — Clare E Heflin*(74) Attorney, Agent, or Firm* — Calfee, Halter & Griswold LLP(57) **CLAIM**

I claim the ornamental design for an LED lamp, as shown and described.

DESCRIPTION

FIG. 1 is a front elevational view of an LED lamp; FIG. 2 is a rear elevational view of the LED lamp of FIG. 1;

FIG. 3 is a right side elevational view of the LED lamp of FIG. 1, the left side elevational view being a mirror image thereof;

FIG. 4 is a bottom plan view of the LED lamp of FIG. 1; FIG. 5 is a front perspective view of the LED lamp of FIGS. 1; and,

FIG. 6 is a rear perspective view of the LED lamp of FIG. 1.

The broken lines shown on the drawings depict portions of the LED lamp that form no part of the claimed design.

1 Claim, 4 Drawing Sheets(56)
